(57) **CLAIM**

The ornamental design for an electrical switch rated connector, as shown and described.

DESCRIPTION

FIG. 1 is a perspective of an electrical switch rated connector;

FIG. 2 is a front elevational view of the electrical switch rated connector;

FIG. 3 is a right elevational view of the electrical switch rated connector;

FIG. 4 is a top plan view of the electrical switch rated connector;

FIG. 5 is a rear elevational view of the electrical switch rated connector;

FIG. 6 is a left elevational view of the electrical switch rated connector; and,

FIG. 7 is a bottom plan view of the electrical switch rated connector.

The broken lines in the drawings illustrate portions of the electrical switch rated connector that form no part of the claimed design.

1 Claim, 7 Drawing Sheets
